(57) **CLAIM**

The ornamental design for a putting green, as shown and described.

DESCRIPTION

FIG. 1 is a front perspective view of a putting green in accordance with a first embodiment of my design;

FIG. 2 is a front elevational view of the putting green of FIG. 1;

FIG. 3 is a rear elevational view of the putting green of FIG. 1;

FIG. 4 is a left side elevational view of the putting green of FIG. 1;

FIG. 5 is a right side elevational view of the putting green of FIG. 1;

FIG. 6 is a top plan view of the putting green of FIG. 1;

FIG. 7 is a bottom plan view of the putting green of FIG. 1;

FIG. 8 is a front perspective view of a putting green in accordance with a second embodiment of my design;

FIG. 9 is a front elevational view of the putting green of FIG. 8;

FIG. 10 is a rear elevational view of the putting green of FIG. 8;

FIG. 11 is a left side elevational view of the putting green of FIG. 8;

FIG. 12 is a right side elevational view of the putting green of FIG. 8;

FIG. 13 is a top plan view of the putting green of FIG. 8; and,

FIG. 14 is a bottom plan view of the putting green of FIG. 8.

The broken lines having consistent dash lengths (dash-dash-dash) represent portions of the putting green that form no part of the claimed design.

1 Claim, 10 Drawing Sheets
